UNITED STATES PATENT OFFICE.

FREDERICK A. GUTH, OF COLUMBUS, OHIO.

MINE DOOR.

Application filed March 17, 1922. Serial No. 544,600.

To all whom it may concern:

Be it known that FREDERICK A. GUTH, a citizen of the United States, residing at Columbus, in the county of Franklin and State of Ohio, has invented certain new and useful Improvements in Mine Doors, of which the following is a specification.

The present invention is directed to improvements in automatic mine doors.

10 The primary object of the invention is to provide a door of this character so constructed that the same will automatically open upon the approach of a mine car from either direction in the tunnel.

15 A further object of the invention is to provide means to overcome the air pressure upon one side of the door. It is a well known fact that in mine tunnels the air pressure upon one side of the door is greater than upon the other side, therefore it is obvious that the doors when opening against this pressure require more power to open, and it is to overcome this condition that the present invention has been perfected.

25 A still further object of the invention is to provide a novel form of hinge for the door, the structure being such that the door can be opened in one direction with less power than the other direction.

30 Still another object of the invention is to provide novel means for protecting the doors against injury when a mine car comes in contact therewith.

With these and other objects in view, as will appear as the description proceeds, the invention consists in the novel features of construction, combinations of elements and arrangements of parts, and hereinafter to be fully described and pointed out in the appended claims.

In the accompanying drawings:

Figure 1 is a top plan view of the door,

Figure 2 is a sectional view on the line 2-2 of Figure 1,

45 Figure 3 is a sectional view on the line 3-3 of Figure 2,

Figure 4 is a sectional view on the line 4-4 of Figure 1,

Figure 5 is a transverse sectional view through one of the hinges,

50 Figure 6 is a vertical sectional view through the same,

Figure 7 is a fragmentary elevation of one of the doors, and

Figure 8 is a detail perspective view of 55 the crank shaft connector.

Referring to the drawing, 1 designates the conventional rails upon opposite sides of which are located the vertical posts 2, said posts being disposed against the sides of the 60 tunnel. The inner surfaces of the post 2 are provided with curved seats 3, and communicating with these seats are bores 4, the purpose of which will appear later. Each door is provided with vertically spaced 65 hinges 5, preferably two in number, but it will be of course understood that the number of hinges may be increased if desired. These hinges consist of boxings 6, the outer faces of which are curved, as at 7, and are 70 adapted to engage the curved seats 3, as clearly shown in Figure 5. These boxings are provided with wings 8, through the medium of which said boxings are secured firmly in the seats 3. By providing the 75 curved seats it is obvious that the wings 8 may be secured in any suitable manner and adjusted so as to be in perfect alignment.

The boxings 6 have their outer ends provided with openings 9 for the reception of 80 the eyes 10 of the bolts 11, said bolts being located in the bores 4 of the posts 2. Surrounding the bolts 11 are coil springs 12, the outer terminals of which bear against the boxings 6, while the inner terminals 85 thereof engage the washers 13, said washers being held in place by the nuts 14. Thus it will be seen that upon manipulating the nuts 14 that the tension of the springs 12 can be conveniently regulated.

The hinges 5 further consist of clamps 15 in which are secured the outer edges of the doors 16, said doors being preferably formed from wood, and are of such size as to fit the tunnel as snugly as possible so as to trap 95 the gases and foul air in the tunnel at the

desired points. These clamps have their outer portions terminating in heads 17, said heads being provided with oblique slots 18, as more clearly illustrated in Figure 5 of the drawing. Operable in the slots 18 are pins 19, the ends of which being engaged in the arms of the yokes 20, said yokes being in turn pivotally engaged by the eyes 10 of the bolts 11.

10 It will be of course understood that the doors 16 are normally in direct alignment and extend transversely of the rails 1. Upon opposite sides of the doors 16 are pivotally mounted independent shafts 21,
15 which are disposed in direct alignment, and have fixed to their outer ends crank arms 22, similar arms 23 being fixed to the shafts intermediate their ends, and connected with the latter shafts are trip bars 24, said bars
20 being preferably of channel formation for the reception of the mine car wheels 25.

The crank arms 22 have their upper ends provided with pins 25' which pivotally engage the upper section 26 of the connectors 27, the lower sections 28 of said connectors having slidably engaged therein rods 29. Upon opposite sides of the sections 28 are arranged coil springs 30 and 31, said springs surrounding the rods 29 and having their adjacent terminals bearing against the adjacent ends of the sections 28. The springs 30 and 31 are held in place on the rods 29 by collars 32, which are adjustable to regulate the tension of the springs 30 and 31.

25 The inner ends of the rods 29 are each provided with stub shafts 33, the purpose of which will later appear. Disposed between the rods 29 are frames 34, the sides 35 of said frames having fixed thereto the 40 inner ends of the bars 36, the outer ends of said bars being pivotally connected to the stub shafts 33 of the rods 29. The bars 36 are slidably mounted in the guides 37 which are secured in any suitable manner to the 45 ends of the ties 38.

Secured to each door 16 adjacent its hinged edge is a bracket 39, said brackets being located within the frames 34.

50 Aligned with the posts 2 and extending longitudinally of the mine tunnel are supports 40, which may be formed of any suitable material, and each support has pivotally mounted upon the inner sides thereof grooved segments 41 to which are secured chain sections 42, said sections being in turn flexibly connected to the doors 16 by the chain sections 43. The segments 41 are further provided with arms 44 upon which are adjustably mounted weights 45. Suitably anchored in the tunnel adjacent the supports 40 are brackets 46, and pivotally connected intermediate their ends to said brackets are levers 47, the upper ends of said levers being provided with notches 48 which are adapted to receive the ends of the arms

44, as clearly shown in Figure 4 of the drawing. The arms 44, when tunnel pressure is exerted upon the left or inner sides of the doors, when closed, will not rest on the bases of the notches. However, when the tunnel pressure is released in the tunnel the arms will rest on the bases of the notches, thus preventing the weights from swinging downwardly and opening the doors. 70 75

Having their inner ends pivotally connected to the pins 25' are rods 49, said rods having fixed thereto collars 50 which are adapted to engage the sleeves 50' which are pivotally connected with the levers 47. The 80 sliding movement of the rods 49 are limited in one direction by the collars 50 contacting with the sleeves 50'.

A chain 51 connects the lower ends of the levers 47 and rods 49, as more clearly shown in Figure 4. 85

It frequently occurs that a mine car will strike the doors of the usual formation which results in injury to both the car and doors, to overcome this objection a novel form of protector is used. This protector consists of metallic bows 52 which are suitably secured to the opposite sides of the doors, and immediately below these bows are secured loops 53. Since the bows and loops are formed from resilient metal it will be apparent that should a mine car strike the same that the shock incident thereto will be absorbed by the bows and loops, and will also prevent metallic parts of the car from striking the doors.

In Figure 1 the doors 16 are shown in their closed positions, and it is apparent that when a car approaches the doors from the right hand side that the wheels of the car will actuate the adjacent trip bars 24, which compresses the adjacent springs 30 and slides the bars 36 inwardly or to the left, whereupon the frames 34 will exert pressure upon the brackets 39, thereby swinging the doors 16 to their open positions, and simultaneously therewith the springs 12 of the hinges will be compressed, as will be obvious. As the bars 36 slide forwardly the springs 30 located on the left hand side of the doors remain in non-compressed conditions, and cooperate with the crank arms 22 to rock the shaft 21 to the left to cause the trip bars 24 on the left hand side of the doors to assume a position in a plane with the other trip bars, and at the same time the rods 29 will be actuated to cause the levers 47 to rock, whereupon the arms 44 will be disengaged from the notches 48. Thus the arms 44 will swing downwardly thus pulling the chain sections 42 and 43. By the addition of the weights 45 the pressure in the tunnel upon the inner or left hand sides of the door will be overcome and permit the doors to open

easily against the pressure in the tunnel. In other words the weights cooperate with the springs 12 to balance the pressure against the doors, and are located upon the pressure side of the doors.

- As soon as the cars engage the trip bars 24 upon the left hand side of the doors the springs 31 will be slightly compressed and maintain the doors 16 in open positions.
- 10 After the cars leave the trip bars 24 on the left hand side of the doors it will be obvious that the springs 12, which have been compressed as the doors swing open, will, during their expansion, draw upon the heads 17, thereby positively swinging the doors to their normal or closed positions. Due to the fact that the air pressure is to the right causes the weights 45 to rise to their normal positions.
- 20 As the doors 16 return to their closed positions the brackets 39 act upon the outer side bars 35 of the frames 34, thereby causing the adjacent bars 36 to move to the right to assume their normal positions, and
- 25 simultaneously the levers 47 are returned to the positions as shown in Figure 4 as the spring 47' retracts. It of course will be understood that said spring has been expanded when the lever 47 was swung to the left, since said spring connects the lever 47 with the supports 40.

When a car approaches the door from the lefthand side the adjacent trip bars 24 will be actuated and the connected parts thereto will operate in the same direction, and at which time the door 16 will swing outwardly or to the right. As soon as the cars engage the trip bars 24 on the left side of the doors the adjacent springs 30 will be compressed and will slide the associated bars 36 to cause the frames 34 to swing the doors, and simultaneously therewith the opposite trip bars are swung downwardly and outwardly. The springs 12 will naturally be compressed and said doors will pull on the chains 43 and 42, thereby causing the arms 44 and their weights 45 to be swung upwardly to a position nearly perpendicular. At the same time the crank arms 22 will be rocked to the right, thereby pulling upon the rods 49 and at which time the chains 51 will pull upon the lower end of the lever 47, thereby rocking the same again to the left to positively free the outer ends of the arms 44 from the notches 48.

The cars upon engagement with the trip bars 24 upon the right hand side will hold the same down, slightly compressing the adjacent springs 31 to move the doors 16 to their open positions to the right. As soon as the cars leave the bars 24 on the right hand side of the doors the springs 12 again act to close the doors, the tripping mechanism being returned to their normal positions, and simultaneously therewith the

springs 47' will swing the levers 47 to the right and in positions so that the arms 44, as they swing downwardly, will engage the notches 48.

Should the trip bars for any reason fail to operate as a car approaches a door the protector, which consists of the bows 52 and loops 53 will be engaged by the adjacent parts of the car so as to absorb the shock of impact between the doors and the car, thus preventing injury to the doors.

In some mines the tunnels are so located that air pressure is not noticeable to an appreciable extent, and in such instances the weights 45 may be eliminated.

It will be further noticed that when a single car or locomotive is on the tracks 1, and between the opposed ends of the trip bars 24 the doors 16 will close after the weight of the car or locomotive has been released upon the trip bars, and it is then that the protector which consists of the bows and loops 52 and 53, respectively, are used. In other words, the doors 16 are opened by the pressure or force of the car or locomotive thereagainst, and in an obvious manner. As soon as a car or locomotive has passed between the doors the same will automatically close under the action of the springs 12.

What is claimed is:

1. In an automatic mine door, a hingedly supported door section, tripping mechanism located on opposite sides of the door and including a pair of movable bars arranged to be actuated by the passage of rolling stock thereover, resilient connections between the bars and said door section operable to swing the door section in a direction governed by the line of travel of the rolling stock, and a resilient hinged mounting for the door section constructed to admit of swinging movement of the door section without necessarily moving the tripping bars.

2. In a mine car door, the combination with a door frame, of door sections pivotally supported by the frame for swinging movement in opposite directions, trip mechanism disposed upon opposite sides of the door sections and operatively connected thereto, resilient connections between the frame and door sections for returning the doors to their closed positions independently of the tripping mechanism, said resilient connection being also operable to permit the door sections to be swung to their open positions independently of said tripping mechanism and independently of each other.

3. In a mine car door, the combination with a pair of hingedly supported door sections, of tripping mechanism located on opposite sides of the door and operatively connected with the door sections to swing the same in a direction in accordance with the line of travel of a mine car, and resilient

- means for swinging the door sections to their closed positions independently of the tripping mechanism and independently of each other.
- 5 4. In an automatic mine door, a pair of swinging door sections, tripping mechanism located on opposite sides of said sections and including movable members arranged to be actuated by the passage of rolling stock
- 10 thereover, resilient connections between said members and said door sections operable to

swing both of said sections in the same direction in accordance with the line of travel of the rolling stock, and a resilient relief mechanism provided in connection with the 15 swinging mounting for each of said door sections constructed to admit of swinging movement on the part of the door sections without necessarily operating the tripping mechanism.

In testimony whereof I affix my signature.
FREDERICK A. GUTH.
